(57) **CLAIM**

The ornamental design for a toilet rim sanitizer cover kit, as shown and described.

DESCRIPTION

FIG. 1 is a bottom plan view of a toilet rim sanitizer cover kit showing my new design showing a cover having a round opening and a cover having an oval opening separated for clarity;

FIG. 2 is a top plan view thereof;

FIG. 3 is a right side elevation view thereof, the opposite side being a mirror image of the shown;

FIG. 4 is a front elevation view thereof;

FIG. 5 is a rear elevation view thereof; and,

FIG. 6 is an isometric view thereof.

The dashed lines shown in FIGS. 1 through 6 represent a perforated tear line.
